UNITED STATES PATENT OFFICE.

EDWIN WILDT AND HENRY HAROLD HOLMES, OF LEICESTER, ENGLAND.

KNITTING MACHINE.

Application filed June 7, 1928, Serial No. 283,508, and in Great Britain January 3, 1927.

This invention consists in improvements in or relating to knitting machines, and while it has particular application to circular knitting machines, it is not limited thereto.

- 5 An object of the present invention is to provide an improved means for producing a pattern in the knitted fabric by a method of yarn-reversal or reverse-plating. The known method of reverse-plating entails feeding 10 simultaneously to the needles two yarns which differ from one another in colour, appearance or character. The yarns are fed at different angles and/or heights so that one is brought to the front of the fabric and the other to the back. When their relative positions are 15 reversed, that yarn which, up to the time of reversal, appeared on the front of the fabric, will be thrown to the back and vice versa. Patterns are produced by repeated reversals 20 in this manner, and an advantage of producing a pattern by reverse-plating lies in the fact that as both yarns are knitted simultaneously, no loose or floating threads appear at the back of the knitted fabric.
- 25 The invention is equally applicable, however, to a method in which only one of the yarns is knitted, while the other remains as a floating thread at the back. In a similar manner the pattern is produced by reversing the 30 relative positions of the yarns.

The term "reverse-plating mechanism" or "reverse-plating" where it occurs hereinafter and in the appended claims, is therefore to be understood as including not only a yarn-reversing mechanism or method in which both 35 yarns are knitted simultaneously, but also a mechanism or method in which only one yarn is knitted.

The invention consists, principally, in 40 means which, for reversing the relative positions at which two yarns are to be fed to the needles, comprise a plurality of sinkers allotted one to each needle at which yarn-interchange is to be effected, a jacquard device, and an operative connection between it 45 and the sinkers.

The above and other features of the invention will be apparent from the following description of a preferred example of reverse-plating mechanism illustrated in the accompanying drawings, in which

Figure 1 is an elevation, partly in section, of one form of the invention applicable to a circular knitting machine having a fixed 55 needle cylinder and a rotatable cam-box, the

plane of the section being radial with respect to the needle cylinder;

Figure 2 shows, in section, the position of a sinker after it has been moved from the position shown in Figure 3 to effect yarn-reversal, and

Figures 3 and 4 are sectional elevations respectively, similar to that in Figure 1, of two modified forms of the invention.

Like reference numerals indicate like parts in the several figures of the drawings.

Referring, first of all, to Figures 1 and 2, only portions of the needle cylinder, cam-box and associated mechanism are illustrated, and a pattern-control mechanism for a relatively small group of needles only is shown. It will be appreciated that the pattern-controlling mechanism illustrated and now to be described can be duplicated at intervals around the machine wherever it is desired to be used so that, if necessary, every single needle in the whole cylinder can be associated with a set of selectors constituting part of the pattern-controlling mechanism.

In the pattern-controlling mechanism illustrated, each needle has appropriated to it a selector for controlling the reverse-plating mechanism, and all the selectors of a group are under the influence of a perforated jacquard band 10.

The selectors or sliders are indicated at 20 and are allocated one to each needle where the knitting is to be influenced by the pattern-controlling (yarn-reversing) mechanism. All these selectors are actuated by the 90 jacquard band 10 so as to be moved forwardly when selected thereby. That is to say, the jacquard band 10 passes over the slotted roller 21 into which spring-pressed pins 22, mounted one in each selector, can enter when selected to do so by a perforation in the jacquard band. The roller 21 has a plurality of longitudinal slots which will register in turn with successive lines of perforations in the jacquard band. The roller is moved round 100 step by step by Geneva stop mechanism comprising a toothed wheel 23, pin 24, worm-wheel 25, and worm 26. The worm is rotated by engagement between a bevel wheel 27 (Figure 1) fast on the worm spindle and a 105 gear ring 28 which is rotated, in a manner to be described later, in company with the cam-box.

For each of the sliders 20, there is an intermediate sliding selector 30, there being, 110

therefore, as many elements 30 as there are sliders 20. Each of the intermediate selectors 30 has an upwardly-directed projection 31 for a purpose to be described more fully 5 hereinafter.

The worm 26 and gear 27 constitute elements in the mechanical drive of the machine. The gear ring 28, which meshes with the gear 27, rotates with the cam-box and 10 consequently serves to rotate with the worm 26 which, through the Geneva stop mechanism above mentioned, will impart to the roller 21 an intermittent step-by-step rotation. Consequently the jacquard band will 15 receive intermittent stepped movements in relation to the pins 22. It will be understood that the mechanism is so timed that the band 10 receives one or more stepped movements in each rotation of the cam-box. The 20 band is first stepped so as to present a line of perforations to a set of pins 22 when the sliders are in their most retracted positions. The completion of the stepped movement of 25 the jacquard roller then moves those sliders which have been selected (i. e. those whose pins 22 have entered perforations in the band 10) towards the cylinder, and in the manner described hereinafter those selectors that are so moved will effect the reversal of the yarn 30 just prior to the laying of the yarns in the respective needles.

The mechanism for effecting reverse-plating comprises a plurality of sinkers, one for each needle which is to participate in reverse-plating or yarn-interchange. In other words, there will be as many sinkers 100 as there are needles at which it is desired to be able to make a yarn-reversal.

Each沉器 has a radially-projecting extension 101 formed with a downwardly-extending portion 102, which latter is forked to receive the upper end of a swinging vertical lever 103. There are as many levers 103 as there are sinkers, one such lever being 45 located to each沉器.

Each lever 103 has a projection 104 of circular outline which is received in correspondingly-shaped tricks formed partly in each of upper and lower rings 105 and 106. The upper ring is secured to the lower one by bolts 107 spaced at intervals around it, and the lower ring is secured to or constitutes a stationary part of the machine. The lower extremity of each lever 103 is turned outwardly 50 at 108 so as to be situated above and to be engageable with a vertically-movable plunger 109. There are as many plungers 109 as there are levers 103 so that for each needle at 55 which it is desired to obtain thread-reversal, there is a set of parts consisting of a selector 20, intermediate selector 30, plunger 109, lever 103 and沉器 100.

All the sinkers are guided in tricks in a fixed ring 110; the levers 103 are guided in 60 tricks formed in rings 105 and 106; and the

plungers 109 are guided in tricks in the lower portion of the ring 106. They are retained therein by means of a lock-ring 111 that is dropped in place and held in position by means of grub-screws 112 which are disposed 70 at intervals around it and bear against the inner extremities of the walls of the plunger tricks.

Tension springs 113, one for each lever 103, tend always to pull the upper ends of the 75 levers away from the needle cylinder. Thus, when the projections 31 are retracted clear of the plungers 109 (as in Figure 1) the latter will be held pressed downwardly by the action of the springs 113 on the levers 103. Under this condition, the sinkers will be 80 moved to the outer limit of their (radial) stroke. When, however, under the selection and influence of the jacquard card 10, a selector 20 and its companion intermediate selector 30 are moved inwardly towards the needle cylinder, the projection 31 of that intermediate selector will be forced under its appropriate plunger 109 and the沉器 100 associated with it is moved inwardly to the position shown in Figure 2.

Each沉器 is formed with a recess 114 and a nose 115 overhanging the recess. Assuming that before inward movement of any individual沉器, the two yarns 116 and 117 are being carried round by their yarn feeders so that they assume the positions shown in Figure 1 in relation to that沉器, it will be understood that when the沉器 is moved inwardly, the nose 115 engages the yarn 117 100 while the yarn 116 passes into the recess 114 as shown in Figure 2. By reference to these two figures, it will be appreciated that the relative position of the yarns is thus reversed, and this reversal can be effected at any needle 105 in accordance with the lay-out of the jacquard card. When the沉器 is moved back again, to its outermost position, the yarns reassume their relative positions indicated in Figure 1.

In order to return the sinkers to their outward position, a return cam is provided in a rotating cam ring 118, and the latter is revolved around the cylinder axis synchronously with the cam-box and yarn guides. Cams 80 and 81 will be employed to return the selectors 20 and 30 respectively. The driving gear for the mechanism according to Figures 1 and 2 is not shown in detail, but it will be understood that any preferred gearing may be employed to drive the moving parts such as the cam-box and yarn guides, cam ring 118, cams such as 80 and 81, and jacquard mechanism.

It is to be understood that the sinkers 100, in addition to effecting a reversal, when required, of the yarns 116 and 117, also perform their normal operation as sinkers. For this purpose they are reciprocated to their full extent after each passage of a yarn or yarns past their respective needles. A cam surface 125

130

for this normal reciprocation will be afforded within the rotatable cam ring 118 in addition to the cam surface which controls their position, as above described, (for yarn reversal) at the time that the needles are about to take the yarn.

In the modification illustrated in Figure 3, the intermediate selector is moved into the path of a cam by the selector, such as 20, and 10 is thereby actuated to move the appropriate sinker. In the form illustrated, instead of an intermediate selector 30 and a separate plunger 109, there is now one element 200 which combines these two features. When, 15 therefore, a selector 20 is moved forwardly, the intermediate selector 200 is moved into the path of a lifting cam 201 of fixed height, thereby tilting the swinging lever 103 to move the sinker in the manner above described. The intermediate selectors 200 and 20 are returned by 20 means of return cams 81 and 80, as in the previous example.

In Figure 4, a further modification is illustrated in which only a single lever 103 is provided for operating all the sinkers. Consequently, only a single plunger 109 is required, and these two members are moved successively into operative relation with each of 30 the sinkers. The upper end of the lever 103 will normally be held outwardly away from the needle cylinder by means of the spring 113, and in this position it will pass through the forks at the tails of the sinkers without moving them radially, except in the case of those sinkers in which a jacquard slider and intermediate selector are moved forwardly by the jacquard mechanism. When such intermediate slider is reached by the plunger, it 40 will ride over the projection 31 and thus tilt the lever 103 so as to move its upper end inwardly, and with it the sinker that it has at that moment engaged. The latter is the sinker which will be appropriate to the selector chosen by the jacquard band. The plunger 109 is at its lower end preferably formed with a chisel- or wedge-shaped extremity in order to permit of its rapid movement on each side of a projection, such as 31, 50 thus allowing the swinging movement of the lever 103 to take place during the short time that will elapse between its entry into and exit from the forked extremity of any one of the sinkers.

The invention as to its details of construction, arrangement and application is capable of many modifications.

For instance, although the invention has been described as applied to a machine having a revolving cam-box, it can, with modifications readily understood to those conversant with the manufacture and design of knitting machines, be applied to a machine having a revolving needle cylinder.

In the examples illustrated herein, the 65 jacquard-controlled mechanisms have been shown as applied to a sector only of the machine. Similar mechanism may be positioned around the periphery of the machine so that the stitches at all the needles, or pre- 70 determined groups of them, are controlled in the manner described. It is not essential that knitting at every individual needle in the cylinder should be subject to the pattern control, as the latter may be applied only at 75 those needles or groups of needles where such control is desirable. Where, therefore, it has been stated hereinabove that a plurality of 80 selectors are employed and are allocated respectively one to each needle or group thereof, it is to be understood that such a statement is intended to include the arrangement in which the stitches at a certain number only of the 85 needles in the machine are to be subject to the pattern control and not the whole number thereof: but where stitches are to be subject to the control, then there will be a plurality of 90 selectors for those needles allocated in the manner above-mentioned.

The invention is not limited in its application to circular knitting machines, as equivalent mechanism can be applied to knitting machines other than those of the circular type.

The invention has been described only in 95 regard to the particular mechanism for actuating and controlling the reverse-plating devices. It is to be understood that other control means, which are customary or requisite and are known in the industry, may or will be 100 employed in accordance with the type and purpose of the machine to which the present invention is applied.

The driving device for the jacquard element, the arrangement and actuation of the 105 selectors and other co-operating portions are very similar to the corresponding arrangements now known and in use, as well as similar to those in the co-pending application No. 283,507 to which reference may be had 110 for a more comprehensive description of these parts.

It is to be understood that in combination with the reverse plating mechanism described herein, there can be employed any 115 preferred mechanism for changing the needle action, for example for producing tuck designs simultaneously with the yarn reversal. One such mechanism has been described in our British Patent No. 283,609, and as this mechanism has been set out in great detail in the said patent, it is unnecessary to describe it again herein. Other known forms of stitch control can, however, be employed, if preferred.

We claim:—

1. In a knitting machine, the combination of yarn-reversing means operable in relation

to two yarns and comprising a plurality of sinkers allotted one to each needle at which yarn-interchange is to be effected, and each sinker mounted to move in a radial direction with respect to the needle cylinder, a jacquard device, and an operative connection between it and the sinkers, said operative connection comprising a plurality of selectors which co-operate with the jacquard device, a selector-controlled actuating member movable under the influence of its associated selector, and a bell-crank interposed between a sinker and the selector-controlled actuating member, the latter being movable in a direction transverse to that in which the sinker moves.

2. In a knitting machine, the combination of yarn-reversing means operable in relation to two yarns and comprising a plurality of sinkers allotted one to each needle at which yarn-interchange is to be effected, and each sinker mounted to move in a radial direction with respect to the needle cylinder, a jacquard device, and an operative connection between it and the sinkers, said operative connection comprising a plurality of selectors which are individually selectable by the jacquard device and are allocated respectively to specific needles whereby each selector always co-operates only with its own needle, a plurality of intermediate selectors one for each selector, a plunger actuated by said intermediate selector, and a bell-crank interposed between a sinker and the plunger, the latter being movable in a direction transverse to that in which the sinker moves.

3. In a knitting machine, the combination of yarn-reversing means operable in relation to two yarns and comprising a plurality of sinkers allotted one to each needle, a jacquard device, an operative connection between it and said sinkers, said operative connection comprising a plurality of selectors which are individually selectable by the jacquard device, intermediate selectors allocated to and movable with each selector during selection by the jacquard device, and a plunger comprising an operative connection between said intermediate selectors and the reversing means and movable in a direction that is transverse to that in which the intermediate selectors are moved during selection by the jacquard element.

4. In a knitting machine, the combination of yarn-reversing means operable in relation to two yarns and comprising a plurality of sinkers allotted one to each needle, a jacquard device, an operative connection between it and said sinkers, said operative connection comprising a plurality of selectors which are individually selectable by the jacquard device, intermediate selectors allocated to and movable with each selector during selection by the jacquard device, and a plurality of plungers which are each movable in a direction that

is transverse to that in which the intermediate selectors are moved during selection by the jacquard element.

5. In a knitting machine, the combination of yarn-reversing means operable in relation to two yarns and comprising a plurality of sinkers allotted one to each needle at which yarn-reversal is to take place, a jacquard device, and an operative connection between it and said sinkers, said operative connection comprising a plurality of selectors which are individually selectable by the jacquard device, intermediate selectors allocated to and movable with each selector, and a plurality of plungers allocated one to each intermediate selector and each formed in one piece with its appropriate intermediate selector, and means operable on said intermediate selectors to actuate the plunger portions when the selectors have been moved to the selected position with the aid of the jacquard device.

6. In a knitting machine, the combination of yarn-reversing means operable in relation to two yarns and comprising a plurality of sinkers allotted one to each needle at which yarn-interchange is to be effected, a jacquard device comprising a perforated element, an operative connection between it and the sinkers comprising a plurality of selectors which have projections to enter perforations in the jacquard element and which are associated with a plunger movable in a direction transverse to the direction of movement of the selectors during selection and with a bell-crank interposed between the plunger and the sinkers.

7. In a circular knitting machine, the combination of the needle cylinder, a plurality of sinkers located adjacent the upper end of the cylinder, a jacquard device located substantially opposite the lower end of the needle cylinder, and an operative connection between the jacquard device and the sinkers comprising a plurality of selectors also located substantially opposite the lower end of the needle cylinder and which are individually selectable by the jacquard device and are allocated respectively to specific needles, and means for translating change in position of the selectors into motion of the respective sinkers, said means being located outside the needle cylinder.

8. In a circular knitting machine, the combination of a needle cylinder, yarn-reversing means comprising a plurality of sinkers located adjacent the upper end of the cylinder, a jacquard device having a pattern extending substantially tangentially of the needle cylinder substantially opposite the lower end thereof, and operating connections between the pattern and the sinkers comprising a plurality of selectors individually selectable by the jacquard device, allocated respectively to specific needles, and extending from the pattern toward the needle cylinder in substan-

tially radial direction, and means between the selectors and the sinkers for translating change in position of the selectors into motion of the respective sinkers, and means for moving the selectors as selected by the pattern.

9. In a knitting machine, the combination of a bed for needles, yarn-reversing means comprising a plurality of sinkers located substantially at a single plane and allotted one 10 to each needle at which yarn-interchange is to be effected, a jacquard device and an operative connection between said jacquard device and said sinkers, said operative connec-

tion comprising a plurality of movable selectors controlled by the jacquard device and located substantially at a single plane different from but substantially parallel to said plane of the sinkers, and lever transmitting mechanism to translate change of position of the selectors into movement by the respective 20 sinkers.

In testimony whereof we have signed our names to this specification.

EDWIN WILDT.

HENRY HAROLD HOLMES.
